CLAIM

The ornamental design for a door for information handling system rack, as shown and described.

DESCRIPTION

FIG. 1 is a perspective view of a door for information handling system rack showing our new design in a first position.

FIG. 2 is a front elevation view of a front portion of the door for information handling system rack in the first position shown in FIG. 1, shown isolated from the rear portion thereof for clarity of illustration.

FIG. 3 is a front elevation view of a rear portion of the door for information handling system rack in the first position shown in FIG. 1, shown isolated from the front portion thereof for clarity of illustration.

FIG. 4 is a front elevation view of the door for information handling system rack in the first position shown in FIG. 1, assembled from the portions thereof shown in FIG. 2 and FIG. 3.

FIG. 5 is a rear elevation view of the door for information handling system rack in the first position shown in FIG. 1. FIG. 6 is a left elevation view of the door for information handling system rack in the first position shown in FIG. 1. FIG. 7 is a right elevation view of the door for information handling system rack in the first position shown in FIG. 1. FIG. 8 is a top plan view of the door for information handling system rack in the first position shown in FIG. 1. FIG. 9 is a bottom plan view of the door for information handling system rack in the first position shown in FIG. 1. FIG. 10 is a perspective view of a door for information handling system rack showing our new design in a second position.

(Continued)

FIG. 11 is a front elevation view of the door for information handling system rack in the second position shown in FIG. 10.

FIG. 12 is a top plan view of the door for information handling system rack in the second position shown in FIG. 10.

FIG. 13 is a perspective view of the door for information handling system rack in the first position shown in FIG. 1, shown with the remainder of an information handling system rack depicted in broken lines to illustrate an environment use; and,

FIG. 14 is a perspective view of the door for information handling system rack in the second position shown in FIG. 10, shown with the remainder of an information handling system rack depicted in broken lines to illustrate an environment use.

All evenly-spaced broken lines are for environmental purposes and do not form part of the claimed design, or designate portions of the door for information handling

system rack that do not form part of the claimed design. All dash-dot lines form boundaries of the claimed design.
